OR D 13,384

EX

Oct 31, 1882

No. 13,384

UNITED STATES PATENT OFFICE.

JOHN L. POPE, OF CLEVELAND, OHIO.

DESIGN FOR A WEAR-IRON.

SPECIFICATION forming part of Design No. 13,384, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and 5 original Design for Wear-Irons, of which the following is a specification, reference being had to the accompanying engraving, forming part thereof.

This invention of mine has reference to a new 10 design for the wear-irons of carriages and other vehicles; and it consists in certain features of ornamentation, which will be hereinafter more particularly described.

In the accompanying engraving it will be 15 seen that the wear-iron is adorned with a round rib or bead, *a*, following the external shape of the upper portion of the article, the ends of which are formed with inner and outer curves, marked respectively *b* and *c*. The lower portion, *d*, of the iron is made rectangular in form,

and is provided with the usual holes at which to attach the article to the desired part of the vehicle. I have cut out the metal at about the middle of the iron, so as to form two oblong artistic openings, as at *e e*.

What I claim as of my invention, and desire to secure by design Letters Patent, is—

1. A wear-iron having the ornamental bead *a* extending around to the ends of the article, and curving inwardly and outwardly thereat, 30 as at *b c*, substantially as shown and described.

2. A wear-iron having its middle portion provided with openings, substantially as shown at *e e*, and herein described.

In testimony whereof I have hereunto set my hand this 22d day of June, 1882.

JOHN L. POPE.

In presence of—

CHAS. W. MOSES,
C. M. COPP.
